UNITED STATES PATENT OFFICE

151,970

DESIGN FOR A SEMI-TRAILER

Ernest Ellberg, Warren, Pa., assignor to
Benjamin F. Mead, Warren, Pa.

Application August 26, 1947, Serial No. 141,069

Term of patent 14 years

(Cl. D14—3)

To all whom it may concern:

Be it known that I, Ernest Ellberg, a citizen of the United States, residing at Warren, in the county of Warren and State of Pennsylvania, have invented a new, original, and ornamental Design for a Semi-Trailer, of which the following is a specification, reference being had to the accompanying drawings forming part thereof, and in which

Fig. 1 is a perspective view of a semi-trailer, showing my new design;

Fig. 2 is an enlarged fragmentary side elevational view of the forward end of the trailer;

Fig. 3 is a front end elevational view of the trailer;

Fig. 4 is a rear end elevational view; and

Fig. 5 is a fragmentary top plan view of that portion of the structure shown in Fig. 2.

I claim:

The ornamental design for a semi-trailer, substantially as shown.

ERNEST ELLBERG.
